FOCUSING AND CENTERING DEVICE FOR
CATHODE-RAY TUBES

Myron R. Heppner, Round Lake, Ill.

Application July 26, 1950, Serial No. 176,033

9 Claims. (Cl. 313—84)

1

This invention relates to improvements in a device for centering and focusing an electron beam in a cathode ray tube upon the fluorescent screen of said tube, and refers particularly to a device of this character which may be mounted upon the external portion of the neck of the tube.

One of the important features of the present invention resides in the provision of a permanent ring magnet which is adapted to embrace the neck of a conventional cathode ray tube, and a magnetic short circuiting device which may be adjustably moved with respect to the permanent magnet to vary the field strength of the magnet and thus provide a convenient means for focusing the electron beam upon the fluorescent screen of the tube.

Another important feature of the present invention resides in a ferromagnetic ring for centering the electron beam with respect to the geometrical center of the tube screen which functions substantially independently of, and does not disturb, the main focusing field, manipulation of the centering device not distorting the picture upon the screen in the manner of many centering devices heretofore proposed.

A further important feature of the present invention resides in a focusing and centering device of the class described which is economical in construction and is simple in operation.

Other features and advantages of the present invention will be apparent from the accompanying drawings and following detailed description.

In the drawings,

Fig. 1 is a side elevational view of a conventional cathode ray tube having my improved focusing and centering device mounted on the neck of the tube.

Fig. 2 is a sectional view taken on line 2—2 of Fig. 1.

Fig. 3 is a fragmentary sectional view taken on line 3—3 of Fig. 2, parts being broken away and parts being shown in section.

Fig. 4 is a detailed sectional view illustrating the universal mount for the centering rod.

Fig. 5 is a detailed sectional view taken on line 5—5 of Fig. 4.

Fig. 6 is a sectional view taken on line 6—6 of Fig. 2.

Fig. 7 is a rear elevational view of the device showing the manner in which the centering device may be eccentrically adjusted relative to the magnet and short circuiting cup.

Fig. 8 is a front elevational view of a modification of the present invention.

2

Fig. 9 is a sectional view taken on line 9—9 of Fig. 8.

Fig. 10 is a sectional view taken on line 10—10 of Fig. 9.

Fig. 11 is a sectional view taken on line 11—11 of Fig. 8.

Referring in detail to the drawing, 1 indicates a conventional cathode ray tube having an enlarged front portion 2 and a neck portion 3. The tube 1 carries the usual fluorescent screen 4 at its front end and is provided with the usual base portion 5 at its rear end, the base portion carrying a plurality of contacts 6 whereby appropriate connections may be made to the tube. 10 My improved focusing and centering device 7 is adapted to be mounted upon the neck 3 of the tube 1 and for purposes of description that end of the device 7 closest to the screen 4 will be hereinafter referred to as the front of the device and that portion of the device closest to the base 5 will be hereinafter referred to as the rear of the device.

The device 7 comprises at its front end a plate 8 which is constructed of a ferromagnetic material. The plate 8 is provided with a central aperture 9 whereby said plate may be positioned in embracing relationship with respect to the neck 3 of the tube 1. That portion of plate 8 which defines aperture 9 is offset as at 16 in Fig. 2, the offset portion providing a seat for a ring magnet 11. The ring magnet 11 may be of the usual aluminum-nickel-iron type commonly known as "Alnico."

An annular ring 12 having an inwardly extending annular flange 12', embraces one end of the ring magnet 11. Ring supports 13 are formed integral with the ring 12 on diametrical opposite sides thereof, the ends of said supports being secured to the plate 8 by any suitable fastening devices, preferably rivets 14. The ring magnet is thus firmly secured to plate 8.

Referring particularly to Figs. 6 and 7 a supporting bracket 15 is secured to the rear face of plate 8 by means of rivets or the like 16, said bracket having an inwardly extending supporting portion 17. The bracket 15 is preferably constructed of a non-magnetic material such as brass, copper, aluminum, or the like. A rod 18 is positioned in an aperture 19 provided in the supporting extension 17, said rod being loosely positioned with respect to said support. One end of said rod is of restricted diameter as indicated at 20 and is positioned in an aperture 21 in plate 8. The end 20 of the rod 18 is peened 30 so as to permit rotation of the rod, but prevent

axial movement thereof with respect to the plate. A collar 22 circumscribes the rod 18 adjacent the rear face of the support 17 whereby axial movement of the rod 18 relative to the plate 8 and support 17 is prevented. The extending end of rod 18 is knurled and is also provided with a slot 18' whereby said rod may be conveniently rotated.

A cup-shaped member 23 is positioned in circumscribing relationship with respect to the magnet 11. The member 23 comprises an annular wall 24 which terminates in an inwardly extending annular flange 25, the wall 24 being spaced from magnet 11. A sleeve 26 is secured at one end in aperture 27 provided in the flange 25, said sleeve being immovable with respect to the flange. The internal portion of the sleeve is provided with screw threads adapted for engagement with external threads 27' formed upon the outer surface of rod 18 between the plate 8 and support 17.

Diametrically opposite from rod 18 a guide pin 28 having a head 29 is rigidly secured to plate 8. Adjacent the rear face of the plate 8 the guide pin has an enlarged portion 30. The opposite end of pin 28 is positioned in slot 31 provided in that portion of flange 25 which is diametrically opposite from sleeve 26. A coil spring 32 embraces pin 28 and is confined between the enlarged portion 30 of said pin and flange 25.

The cup-shaped member 23 is constructed of a ferromagnetic metal. As will be hereinafter more fully described the cup-shaped member 23 provides a magnetic short circuit for the magnet 11.

A ring 33, constructed of a ferromagnetic material, is slidably positioned upon flange 25, the ring 33 carrying a radially outwardly extending lug 34. Lug 34 is provided with an elongated slot 35 and a screw 36 embraced by a spring 40 washer 37 passes through slot 35 and is threadedly positioned in flange 25. If desired the screw 36 and washer 37 may be replaced by a rivet whose head is spaced from flange 25.

Diametrically opposite the lug 34 ring 33 carries a radially outwardly extending actuating lug 38. Lug 38 is provided with an aperture 39 in which a control rod 40 is loosely positioned. A socket 41 (Fig. 4) having a plurality of spring pressed fingers 42 is carried by plate 8 and the end of control rod 40 terminates in ball 43 which is positioned within the socket, the arrangement being such that rod 40 may be rotated about its axis or may be pivoted a limited distance about the ball 43 within the socket. In view of the fact that an intermediate portion of the control rod 40 is in contact with the lug 38 swingable movement of the control rod results in slidable movement of the ring 33 parallel to the face of flange 25, it being possible to move the ring 33 in substantially any direction in the plane parallel to the annular flange 25. Lug 38 is also provided with a slot 38' in which the end of pin 28 projects, said slot functioning to limit movement of the ring 33. A strip 40' is carried upon flange 25 and functions to prevent unintended removal of ring 33 from flange 25.

In operation, the device 7 is positioned upon the neck 3 of the cathode ray tube 1, the interior diameter of the magnet 11 being larger than the exterior diameter of the neck 3. The plate 8 is provided with bolt holes 44 whereby the plate, carrying the elements hereinbefore described may be mounted upon a suitable support 45', which may conveniently be one of the

7 tube supports for mounting the tube in the chassis.

The magnetic lines of force which emanate from the magnet 3 and pass through the neck portion of the tube are dependent upon the permeability or susceptibility of the environment adjacent the magnet. By the provision of the cup-shaped member 23 constructed of a ferromagnetic material a greater or lesser amount of magnetic flux may be diverted through the cup depending upon its position with respect to the magnet. By rotating rod 18 the cup-shaped member 23, which in effect is a short circuiting device for the magnetic flux, may be moved axially with respect to the magnet 11. In this fashion the effective strength of the magnet 11 with respect to the field which it produces within the cathode ray tube neck may be changed. By this means a convenient focusing device is provided for the proper focusing of the electronic beam upon the fluorescent screen 4.

To center the electronic beam upon the fluorescent screen rod 40 may be manipulated to change the position of ring 33 with respect to the annular flange 25. As shown in broken lines in Fig. 7 rod 40 may be so manipulated as to dispose ring 33 in substantially any desired eccentric position with respect to the annular flange 25. In this fashion the magnetic field established by the short circuiting cup 23 may be distorted or altered thereby tending to alter the position of the electron beam within the tube. It will be noted that the alteration in the magnetic field is brought about by a change in the effective flux path of the short circuited flux and in this fashion the proper centering of the beam may be brought about without materially distorting or changing the focusing adjustment since the distortion is brought about in the short circuited field rather than in the main field.

Referring particularly to Figs. 8 to 11 inclusive, a modification of the invention is shown, wherein in 45 indicates a ferromagnetic plate, similar to plate 8 and having a central aperture 46. An offset seat 47 is formed adjacent the defining edge of aperture 46 for the reception of a permanent magnet 48, similar to magnet 11. Magnet 11 may be carried by a tubular member 49 having an annular flange 50 for abutting the rear face of the magnet. The front portion of the tubular member is expanded outwardly, as indicated at 51 in Fig. 9, whereby to secure the tubular member carrying the magnet to plate 45. The tubular member 49 is constructed of aluminum, brass or other non-magnetic material.

A cup-shaped member 52, similar to the member 23 hereinbefore described circumscribes magnet 48 and functions as a magnetic short-circuiting device for a portion of the flux from the magnet. The cup-shaped member 52 carries an inwardly extending flange 53 in which a threaded sleeve 54 is retained, the sleeve cooperating with adjusting screw 55 to axially move the cup-shaped member relative to the magnet to control the focusing of the electron beam, as hereinbefore described. Screw 55 is supported by bracket 56 and one end of the screw is journaled in plate 45, similar to the arrangement hereinbefore described in conjunction with screw 27.

Diametrically opposite screw 55 a pin 57 is carried by plate 45 and extends through opening 58 in flange 53. A coil spring 59 embraces pin 57 and functions to bias that portion of cup 52 opposite to screw 55 so as to secure uniform

axial movement of all portions of the cup when the screw 55 is manipulated.

An annular ferromagnetic plate 60 is secured by means of screw 61 to flange 63. It has been found that an increase in the sectional path of the leakage flux at this zone is advantageous in focusing the beam. The plate 60 is preferably concentric with the flange opening, but if desired it may be rendered eccentric thereto by the manipulation of screw 61.

As a feature of the present form of the invention an annular collar 62 is slidably carried upon the inner surface of plate 45. The collar is constructed of a ferromagnetic material and carries an inwardly extending annular flange 63 the interior diameter of which is greater than the exterior diameter of the magnet 48 whereby the flange 63 of the collar may be radially spaced from the outer surface of the magnet. The collar 62 also carries an annular flange 64 which contacts the surface of plate 45 and is disposed parallel to said surface. The flange 64 carries a tongue 65, provided with a slot 66 which is engageable with guide pin 67 carried by plate 45. Diametrically opposite from tongue 65, the flange 64 carries a manipulating extension or handle 68. A slot 69 is provided in the extension 68 whereby said collar can be slidably moved in all directions a limited distance without being obstructed by pin 57. A second slot 70 is provided in extension 68 and a guide plate 71 is slidably positioned upon the extension, said guide plate also being provided with slot 72 of relatively restricted width. A screw 73 is carried by plate 45 and extends through both slots 70 in extension 68 and slot 72 in guide plate 71, said screw serving as a guide to the transverse movement of the extension.

The movable collar 62 may be employed as a centering device for the electron beam, functioning, in effect as an independent eccentrically movable short-circuit for flux other than the flux within the magnet confines, that is, the main flux field. The collar may be moved in a direction longitudinal with respect to finger 65 and extension 68, the movement being guided by screw 67 in slot 66, and extension 68 slidably moving with respect to screw 73 and guide plate 71, or the collar may be moved by moving the extension 68 transversely whereby the movement will be guided by screw 73 in slot 72. In all cases, however, the movement is so constrained as to prevent contact of the collar 62 and the magnet 48.

It has been found in devices heretofore proposed for focusing and centering an electron beam that when the beam is properly focused, the operation of centering the beam results in distortion of the circular beam upon the screen, usually rendering it more or less oval. In the present device, after the beam has been properly focused the circular beam may be moved, by manipulating the centering adjustment without altering or distorting the circular contour of the beam on the screen. This is believed to be brought about by the fact that the flux employed in centering in all cases constitutes short-circuited flux and does not require substantial interference with the main focusing flux within the ring magnet.

It can readily be seen that herein is provided a device which is of economical construction; can be readily mounted upon a conventional cathode ray tube; is simple to manipulate, and performs the function of focusing and centering the elec-

tron beam without having the centering adjustment materially interfere with the focusing adjustment.

I claim as my invention:

- 5 1. In a focusing and centering device for an electron beam in a cathode ray tube which comprises, a frame, a permanent magnet carried by said frame for embracing a portion of the neck of a cathode ray tube and establishing a main magnetic field, a magnetic short-circuiting device carried by said frame in circumscribing relationship with respect to and spaced from a portion of said magnet, means for changing the position of said short-circuiting device with respect to 10 said magnet along the length of the tube neck to change the main magnetic field in the tube to focus the electron beam, and means magnetically contacting said short-circuiting device for laterally changing the short-circuited flux path 15 relative to the axis of the neck of the tube to center the electron beam passing through said neck upon the screen of the tube.
2. In a focusing and centering device for an electron beam in a cathode ray tube which comprises, a frame, a permanent magnet carried by 25 said frame for embracing a portion of the neck of a cathode ray tube and establishing a main magnetic field, means for establishing a short-circuit magnetic path of relatively low reluctance 30 radially spaced outwardly from said magnet, means for changing the effective reluctance of said short-circuit path to change the strength of the main field and focus the electron beam passing through the neck of the tube, and movable ferro-magnetic means contacting said short-circuiting means for radially changing a portion 35 of the short-circuit path to center the electron beam passing through the neck of said tube upon the screen of the tube.
3. In a focusing and centering device for an electron beam in a cathode ray tube which comprises, a frame, a permanent magnet carried by 45 said frame for embracing a portion of the neck of a cathode ray tube, a magnetic short-circuiting device carried by said frame in circumscribing relationship with respect to and spaced from a portion of said magnet, means for changing the position of said short-circuiting device with respect to said magnet along the length of the 50 tube neck to change the strength of the magnetic field in the tube to focus the electron beam, and a ferro-magnetic ring adapted to embrace the neck of the tube and carried by said short-circuiting device for eccentric movement relative thereto and relative to the neck of the tube for centering the electron beam passing through the neck of the tube.
4. In a focusing and centering device for an 60 electron beam in a cathode ray tube which comprises, a frame, a permanent ring magnet carried by said frame for embracing a portion of the neck of a cathode ray tube, an annular magnetic short-circuiting device carried by said frame in circumscribing relationship with respect to and spaced from a portion of said magnet, means for changing the position of said short-circuiting device with respect to said magnet along the 65 length of the tube neck to change the strength of the magnetic field in the tube to focus the electron beam, and a ferro-magnetic ring adapted to embrace the neck of the tube and carried by said annular short-circuiting device in magnetic contact therewith and for eccentric movement 70 relative thereto and relative to the neck of the 75 tube.

tube for centering the electron beam passing through the neck of the tube.

5. In a focusing and centering device for an electron beam in a cathode ray tube which comprises, a frame, a permanent ring magnet carried by said frame for embracing a portion of the neck of a cathode ray tube, an annular magnetic short-circuiting device carried by said frame in circumscribing coaxial relationship with and spaced from a portion of said magnet, means for moving the said short-circuiting device axially with respect to said magnet along the length of the tube neck to change the magnetic field in the tube to focus the electron beam, and a ferro-magnetic ring spaced from said ring magnet and adapted to embrace the neck of the tube, said ferro-magnetic ring being carried by and in magnetic contact with said annular short-circuiting device for eccentric movement relative thereto and relative to the neck of the tube for centering the electron beam passing through the neck of the tube.

6. In a focusing and centering device for an electron beam in a cathode ray tube which comprises, a frame constructed of ferro-magnetic material, a permanent ring magnet carried by said frame and adapted to embrace a portion of the neck of a cathode ray tube, a magnetic short-circuiting device, non-magnetic support for carrying said device upon said frame in circumscribing coaxial relationship with and spaced from a portion of said magnet, non-magnetic means for changing the position of said short-circuiting device with respect to said magnet along the length of the tube neck to change the magnetic field in the tube to focus the electron beam, and a ferro-magnetic ring adapted to embrace the neck of the tube and carried only by and in magnetic contact with said short-circuiting device for eccentric movement relative thereto and relative to the neck of the tube for centering the electron beam passing through the neck of the tube.

7. In a focusing and centering device for an electron beam in a cathode ray tube which comprises, a frame, an annular magnet carried by said frame for embracing a portion of the neck of a cathode ray tube, a cup-shaped magnetic short-circuiting device having an inwardly extending annular flange carried by said frame in circumscribing coaxial relationship with and spaced from a portion of said magnet, means for changing the axial position of said short-circuiting device with respect to said magnet along the length of the tube neck to change the strength of the magnetic field in the tube to focus the electron beam, and a ferro-magnetic ring adapted to embrace the neck of the tube and slidably mounted upon and in magnetic contact with the annular flange of said short-circuiting device for eccentric movement relative thereto in the plane of said flange and relative to the neck of the tube for centering the electron beam passing through the neck of the tube.

8. In a focusing and centering device for an electron beam in a cathode ray tube which comprises, a frame, an annular magnet carried by

said frame for embracing a portion of the neck of a cathode ray tube, a cup-shaped magnetic short-circuiting device having an inwardly extending annular flange carried by said frame in circumscribing coaxial relationship with and spaced from a portion of said magnet, means for changing the axial position of said short-circuiting device with respect to said magnet along the length of the tube neck to change the magnetic field in the tube to focus the electron beam, a ferro-magnetic ring adapted to embrace the neck of the tube and slidably mounted upon the annular flange of said short-circuiting device for eccentric movement relative thereto and relative to the neck of the tube for centering the electron beam passing through the neck of the tube, and an actuating rod pivoted to said frame and connected to said ring for sliding said ring upon the flange of the short-circuiting device.

20 9. In a focusing and centering device for an electron beam in a cathode ray tube which comprises, a frame, a permanent ring magnet carried by said frame for embracing a portion of the neck of a cathode ray tube and establish a main 25 magnetic field within said ring in the neck of the tube, means for establishing a short-circuit magnetic path radially spaced outwardly from said magnet, said means comprising a ferro-magnetic annular member circumscribing and spaced radially outwardly from said magnet, and a ferro-magnetic collar carried by said annular member and circumscribing said tube neck and spaced axially from said magnet, means for axially moving said annular member to focus the electron 30 beam of the tube, and independent means for eccentrically positioning said collar to center the electron beam.
